UNITED STATES PATENT OFFICE.

HENRY SYNCK, OF COLDWATER, OHIO, ASSIGNOR, BY MESNE ASSIGNMENTS, TO THE NEW IDEA SPREADER COMPANY, OF COLDWATER, OHIO, A CORPORATION OF OHIO.

MANURE SPREADER.

Application filed June 9, 1919. Serial No. 302,654.

To all whom it may concern:

Be it known that I, HENRY SYNCK, a citizen of the United States, and a resident of Coldwater, in the county of Mercer and State of Ohio, have invented certain new and useful Improvements in Manure Spreaders, of which the following is a full, clear, and exact description.

The invention relates to manure-spreaders.

One object of the invention is to provide an improved construction in which provision is made for preventing the manure from becoming wrapped around and entangled with the tooth-supporting bars of the cylinder.

Another object of the invention is to provide improved means for preventing the tooth-carrying bars of the cylinder from cutting into the sides of the box or frame.

Another object of the invention is to provide an improved construction of the cylinder which is durable and efficient in operation.

A still further object of the invention is to provide improved means for preventing the rear axle from binding in the bearings which are secured to the sides of the conveyor-box.

The invention consists in the several novel features hereinafter set forth and more particularly defined by claims at the conclusion hereof.

In the drawings: Fig. 1 is a vertical longitudinal section of the rear portion of a manure-spreader embodying the invention. Fig. 2 is a detail of one of the connections between one of the heads and one of the tooth-supporting bars. Fig. 3 is a section taken on line 3—3 of Fig. 1. Fig. 4 is a detail section of one of the axle-bearings and Fig. 5 is a perspective of the bearing-sleeve. Fig. 6 is a detail of one end of the band adjacent one end of the lower cylinder.

The invention is exemplified in a spreader comprising a box having sides 7 and a bottom 7^a, an endless chain and seat conveyor 8, a distributer-cylinder 9, an upper cylinder 10, an axle 11, and carrying wheels 12. In the type of spreader illustrated, the cylinders and conveyor are usually driven by power derived from the wheel axle and through suitable gearing, as well understood in the art. Only the rear portion of the spreader has been illustrated, because the invention is embodied in that, and the front

portion may be of any suitable or well known construction.

The distributer cylinder 9 is mounted upon a shaft 13 which is carried by bearings 14 and extends through the box-sides 7, and comprises a pair of heads 15 each of which has a hub secured to the shaft 13 and curved laterally extending lugs 17, each adapted to receive a tubular bar 18 in which the cylinder-teeth 19 are fixed. Bolts 20 extending through lugs 17 and bars 18 secure each bar rigidly on the heads. Each lug is provided with an outwardly open seat 21 which is provided with a recess 22 disposed inwardly of the bar, so that, when the nut of the bolt 20 forces the bar 18 into the seat, it will permit slight distortion of the tubular bar into said recess which will cause the bar to be more firmly clamped in the seat. As the result of employing round or tubular tooth-supporting bars and open seats in the heads, tendency for the manure to become entangled adjacent and around the heads is minimized. The teeth 19 are driven through the tubular bars 18 and fixedly held therein. A band 25 is provided at each end of the cylinder 9 and each of these bands is provided with a member 26 abutting against the inner face of a box-side 7 and secured in position by bolts 27 and comprises also an inverted flange 28 which is outside of and laps the ends of the bars 18 to prevent the manure from becoming entangled and wrapped around said ends. The member 26 of band 25 prevents the bars 18 from cutting into the sides 7 which are usually formed of wood, in event there should be any lateral play of the cylinder. Each band is cut away at its rear end and its lower end is curved as at 25' to centralize the bars 18.

The upper cylinder is mounted on a shaft 30 and comprises heads 31, tubular bars 32 secured to said heads, and teeth 33 secured in said bars. The bars 32 are secured to the heads 31 in manner hereinbefore described in connection with the bars and heads of the distributer-cylinder 9. A deflecting ring or plate 34 is provided at each end of the cylinder 10 and has a curved flange 35 which extends to a point inwardly of the ends of the bars 32 and serves to deflect the manure from the ends of said bars so that it will not become wrapped around or entangled with them. Said rings are secured to the box-sides 7 by bolts 36.

Mechanism for driving the cylinders is exemplified by a sprocket 37 suitably driven by the axle 11, a chain 38 which extends around sprockets 39 and 40 on the shafts 13 and 30 respectively to drive the cylinders 9 and 10.

In practice, it sometimes occurs that the parts of the frame-work or box are not truly aligned or become distorted. This subjects the rear axle and its bearings to binding stresses which causes excessive wear. To meet this difficulty, the axle-bearings 43, which are secured to the box-sides 7 respectively, are provided with sleeves 44. Each sleeve is slightly tapered as at 45 to permit sufficient movement in the bearing so that binding will be avoided when the box sides are distorted, and so that the sleeves at the sides of the axle will be automatically aligned by the axle instead of being subjected to cramping when bearings are not truly aligned. Each sleeve is provided with a lug 47 which fits into a correspondingly shaped notch 48 in the bearing 43 to hold the sleeve against rotation in the bearing and a grease-cup 49 is secured in said lug so that lubricant will be supplied to the bearing surfaces between the sleeve and the axle. If the sleeve should become worn, it can be withdrawn from the bearing and replaced without removing or replacing the bearing 43.

The invention exemplifies a manure spreader in which provision is made for preventing the manure from becoming wrapped around or entangled with the tooth-carrying bars; in which provision is made for preventing said bars from cutting the sides of

the box, in which provision is made for preventing excessive wear between the axle and its bearings and which permit ready replacement of the bearing-sleeve when desired.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a fertilizer distributor, the combination of a receptacle for the fertilizer, a cylinder comprising tooth-carrying bars, and a metallic band fixedly secured on the inside of the receptacle and provided with a member between the ends of the bars and the receptacle sides disposed to prevent the bars from engaging said sides and a flange extending inwardly to longitudinally lap the outer faces of the bars.

2. In a fertilizer distributor, the combination of a receptacle for the fertilizer, a cylinder comprising tooth carrying bars, and a metallic band fixedly secured on the inside of the receptacle and provided with a member between the ends of the bars and the receptacle sides disposed to prevent the bars from engaging said sides and a flange extending inwardly to longitudinally lap the outer faces of the bars, said band being non-continuous and having one of its ends curved longitudinally of and outwardly from the cylinder.

HENRY SYNCK.
